(57) **CLAIM**

The ornamental design for an ottoman with flip pocket, as shown and described.

DESCRIPTION

FIG. 1 is a perspective view of my new design of an ottoman having a flip pocket in a resting or nearly resting external position;

FIG. 2 is an exploded perspective view thereof and showing a raised top cushion;

FIG. 3 is a perspective view thereof with flip pocket partially lifted;

FIG. 4 is a plan view thereof with top cushion removed for clarity and showing flip pocket positioned outside the arrangement;

FIG. 5 is a front elevation view thereof;

FIG. 6 is a right elevation view thereof;

FIG. 7 is a plan view thereof with top cushion removed for clarity and showing flip pocket positioned internally;

FIG. 8 is a perspective view of a second embodiment of my new design of an ottoman having a flip pocket in a resting or nearly resting external position;

FIG. 9 is an exploded perspective view thereof and showing a raised top cushion;

FIG. 10 is a perspective view thereof with flip pocket partially lifted;

FIG. 11 is a plan view thereof with top cushion removed for clarity and showing flip pocket positioned outside the arrangement;

FIG. 12 is a front elevation view thereof;

FIG. 13 is a right elevation view thereof;

FIG. 14 is a plan view thereof with top cushion removed for clarity and showing inner pocket and flip pocket positioned internally;

FIG. 15 is a perspective view thereof with top cushion removed for clarity and showing inner pocket and flip pocket;

FIG. 16 is a perspective view of a third embodiment of my new design of an ottoman having two flip pockets with one flip pocket in a resting or nearly resting positions and the other flip pocket partially lifted;

FIG. 17 is a plan view thereof with top cushion removed for clarity and showing the two flip pockets positioned outside the arrangement;

FIG. 18 is a front elevation view thereof; and,

FIG. 19 is a plan view thereof with top cushion removed for clarity and the two flip pockets positioned internally.

The broken lines shown in the drawings are for illustrative purposes only and form no part of the claimed design.
